DESIGN FOR A BOTTLE OR SIMILAR
CONTAINERRegina Rose Bachinsky and John Bachinsky,
Pittsfield, Mass.

Application February 5, 1946, Serial No. 126,260

Term of patent 14 years

(Cl. D58—9)

To all whom it may concern:

Be it known that we, Regina Rose Bachinsky and John Bachinsky, citizens of the United States, residing at Pittsfield, in the county of Berkshire and State of Massachusetts, have invented a new, original, and ornamental Design for a Bottle or Similar Container, of which the following is a specification, reference being had to the accompanying drawing, forming a part thereof in which—

Fig. 1 is a front elevational view of a bottle or similar container showing our new design;

Fig. 2 is a left hand side view thereof.

Referring to the drawings, the bottle comprises a heart shaped container mounted on a pedestal with an arrow running through the container as shown. The pointed end of the arrow is made integral with the container while the feathered end forms the stopper for the container.

We claim:

The ornamental design for a bottle or similar container, as shown and described.

REGINA ROSE BACHINSKY.
JOHN BACHINSKY.
